UNITED STATES PATENT OFFICE.

GUSTAVE HOEFER, OF CHAMPOEG, OREGON.

METAL-CUTTING TOOL.

SPECIFICATION forming part of Letters Patent No. 319,816, dated June 9, 1885.

Application filed July 24, 1884. (No model.)

To all whom it may concern:

Be it known that I, GUSTAVE HOEFER, a citizen of the United States of America, residing at Champoeg, in the county of Marion 5 and State of Oregon, have invented certain new and useful Improvements in Metal-Cutting Tools; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to certain improvements in devices for holding metal while being cut, the object of my invention being to provide an implement which may be employed for trimming and holding sheet-metal plates; and to this end my invention consists in an attachment for anvils or other such structures having a solid foundation, which attachment consists in a spring or bar which has a portion doubled upon itself, a block 20 against which the free end of the spring abuts, a screw for regulating the distance between the end of the spring and the upper surface of the block, and a gage, and means for holding the block and spring in position, as will 25 be hereinafter set forth.

30 My invention also consists in the construction and combination of the parts, as will be hereinafter more fully set forth and pointed out in the claims.

35 In the accompanying drawings, which illustrate my invention, Figure 1 is a side view, Fig. 2 a sectional view, Fig. 3 a vertical sectional view, Fig. 4 a perspective view, of an implement which is employed in connection 40 with the holder for trimming the metal.

A represents the base, which is adapted to be attached to an anvil or other solid foundation, and is for this purpose provided with a transverse groove, a. One end of this base A 45 is provided with a vertical opening, B, which has an inclined side, b, and is adapted to receive and retain the bent portion of the spring, the base portion of a block, and a wedge for retaining these parts within the opening B, 50 as will be hereinafter fully set forth.

C represents the base of a holding spring,

which has a portion, C', bent at right angles therewith, the portion C" being curved upwardly, as shown, while the portion C'" is bent outwardly and extends beyond the end of 55 the portion C. This spring is formed of a single piece of metal of suitable thickness, and is tempered and bent so that its ends will have a tendency to bear upon or toward each other.

The spring hereinbefore described is provided, adjacent to its curved portion C", with a screw-threaded perforation, c, for the reception of an adjusting-screw, D, the lower end of which fits within a threaded recess, c', formed immediately under the threaded perforation c. By means of this adjusting-screw 60 the position of the portion C" of the spring relative to the block may be varied to accommodate different thicknesses of metal.

E represents a block or anvil, which is provided upon opposite sides with shoulders. This anvil is secured in the opening B immediately under the end of the spring by a wedge, F, which wedge holds the spring and block 65 within the opening B.

A sliding or adjustable gage, G, is retained in position upon the straight portion or base C of the spring by means of an adjusting-screw, H, which passes through a bifurcated portion of the gage into a screw-threaded 80 opening in the spring, as shown. The gage G has one end of the same bent upward at right angles, and may be provided, when desired, with a central nib or projection, g, when the gage is intended to be used and the implement employed for cutting circular sheet-metal plates.

The end of the spring-holder C'" has one corner rounded, while the opposite corner is formed so as to present a right angle, and the 85 edges of the block E are similarly constructed. In Fig. 4 I have shown a hammer having a cutting-face, I, which is adapted to be employed with my improved implement, the cutting-edge of this hammer being wedge-shaped 90 and curved, as shown.

The operation of my invention is as follows:

When it is desired to cut strips of metal so that they will have a straight edge, the gage G 95 is adjusted by moving the same forward or rearwardly, according to the length of strips

desired, suitable marks being provided upon the gage and base of the spring. The strip is then inserted between the upper face of the block and lower portion of the end C'', the cutting being performed by the face of the hammer I, which rests upon the metal adjacent to the vertical end of the portion C''.
5

When it is desired to cut circular plates of metal, the gage having the central nib, g, is 10 employed, and the metal is turned upon said point. By the means hereinbefore described I am enabled to provide an implement or device which is simple in construction and effective in operation, and a labor-saving 15 device.

One of the uses to which my invention may be put is the cutting of sheet-metal strips which are employed for securing the tops upon wooden packages—as butter-firkins, &c.— 20 and the cutting of circular metal plates for covering the bung-holes of barrels or casks. Though I have mentioned these uses, it is evident that my invention may be employed for numerous other purposes.

25 Having thus described my invention, what I claim as new, and desire to secure by Letters Patent, is—

1. A holder for sheet metal adapted to be employed in connection with the cutting means, 30 consisting of a block or anvil and a spring and

spring-holder secured to a common base, so that the end of the spring-holder will lie immediately above the outer face of the anvil, and a regulating-screw for adjusting the position of the holder toward the anvil, substantially as shown, and for the purpose specified.
35

2. In combination, with a base having an opening, B, formed therein, a bent spring having members C C' C'' C'', a regulating-screw attached to its upper portion and bearing upon its lower side an adjustable gage, and an anvil or block, E, the parts being combined and organized substantially as set forth.
40

3. In a device for holding and gaging sheet metal, an anvil or block, E, a spring bent upon itself and having one end located above the anvil, a screw for adjusting the pressure of the spring upon the anvil, and an adjustable sliding gage secured between the bent portion of the spring and to one member thereof, and 45 a wedge or equivalent for securing the spring and anvil to a base, the parts being combined and organized substantially as shown.
50

In testimony whereof I affix my signature in presence of two witnesses.

GUSTAVE HOEFER.
